TRACK GRINDER

Henry J. Perazzoli, Philadelphia, Pa.

Application April 22, 1933, Serial No. 667,448

4 Claims. (Cl. 51—178)

This invention relates to new and useful improvements in railway track grinding machines and has particular relation to machines of this general character wherein grinding is effected by reciprocating an abrasive block or blocks longitudinally on the surface of track rails.

The principal object of the invention is to provide a machine of the general character set forth arranged to travel on the rails to be ground wherein the source of power operable to reciprocate the abrasive elements on the rails is available to propel the machine in its entirety from place to place along the track.

Another important object of the invention is to provide a machine of the general character set forth having novel means operable at will in conjunction with a source of motive power whereby the machine may be driven in either direction on the track at various speeds.

A more specific object of the invention is to provide a machine of the general character set forth having an internal combustion engine equipped with the usual change speed transmission comprising three speeds in one direction and one speed in the opposite or reverse direction, together with novel means operable at will to render the three speeds, otherwise available for travel of the machine in but one direction, available to propel the machine in either direction on the track.

A further specific object of the invention resides in the novel manner in which the shaft through which power from the motor is imparted to the abrasive elements to reciprocate the same is mounted with respect to the main frame of the machine together with novel means associated with said mounting to permit the position of the shaft to be adjusted for the purpose of taking up slack or play in the driving connections.

Another object of the invention is to provide a machine of the general character set forth having means operable to elevate the abrasive elements out of contact with the track rails during movement of the entire machine therealong.

The invention contemplates in addition, numerous other features and novel structural details which are set forth hereinafter and disclosed in the accompanying drawings in which:

Figure 1 is a view in perspective of the machine forming the subject of the present invention;

Fig. 2 is a view in perspective of the machine disclosed in Fig. 1 with the body or super structure removed therefrom to better display the operable mechanisms of the machine to which the present invention is particularly directed;

Fig. 3 is an enlarged view in section through the novel direction control mechanism on line 3—3, Fig. 2;

Fig. 4 is an enlarged view in section on line 4—4, Fig. 3;

Fig. 5 is a view in section on line 5—5, Fig. 4;

Fig. 6 is an enlarged plan view of the central portion of the disclosure in Fig. 3, showing the relation of the various parts of the direction control mechanism in the neutral position;

Fig. 7 is an enlarged fragmentary plan view showing the novel mounting of and means for adjusting the intermediate drive shaft for the abrasive elements;

Fig. 8 is a view in side elevation of the disclosure in Fig. 7;

Fig. 9 is an enlarged detail partly in section of the mounting of the abrasive elements; and

Fig. 10 is a view similar to the disclosure in Fig. 9 showing a modification of the means for controlling the relative vertical position of the abrasive elements with respect to the track rails.

Referring now more particularly to the drawings, the machine comprises longitudinal and transverse side and end frame members 1 and 2 respectively, and center sills 3. Axles 4 are mounted below and adjacent each end of the frame transversely with respect thereto, said axles 4 being mounted against springs (not shown) contained within housings 5 secured to the main frame of the machine. Traction wheels 6 are mounted at each end of the axles 4 beyond the side frame members 1 and are arranged to travel upon the track rails 7 to be ground. In the present instance an internal combustion engine M constitutes the motive power for the various operative mechanisms of the machine, and the engine is supported by the frame and positioned longitudinally with respect thereto. The motor M in the present instance is of the ordinary automobile or truck type comprising the usual change speed transmission T, shift lever 8 and clutch lever 9.

The novel mechanism operable to change the effective direction of rotation derived from the motor M for transmission to the various mechanisms of the machine, is contained within a housing 10 secured to the rear end of the transmission T, and the drive shaft 11 extends into said housing 10, being supported therein by a bearing 12. A beveled gear 13 having teeth 14 is mounted on the end of said shaft 11 by means of a key 15 and arranged for rotation therewith. A shaft 16, constituting the main operating shaft of the machine, extends transversely through the center 55

- of the housing 10 and has its ends journaled in bearings 17 in brackets 17a mounted on the side frame and sill members 1 and 3 respectively.
- 5 A collar 18 is slidably mounted on the shaft 16 within the housing 10 by means of keys 19 which, though permitting said collar to move longitudinally with respect to said shaft, prevent relative rotation of the collar and shaft.
- 10 An annular planetary or face gear 20 is mounted at each end of the collar 18 and these gears are of such diameter that upon movement of said collar 18 on the shaft 16 in either direction, the teeth 21 of one of said gears 20 will mesh with the teeth 14 of the beveled gear 13 on the drive shaft 11.

An annular groove 22 is formed in the collar 18 and arranged to receive a cam member 23, the inner concave surface of which is doubly arced as shown at 24 and 25 for the purpose of eliminating any possible binding of said cam 23 in the annular groove 22. The upper or convex surface of the cam 23 is provided with a hole 26 to receive an eccentric pin 27 extending from the bottom of a circular bushing 28 which is similarly provided with an eccentrically positioned hole 29 in the top thereof to receive the end of a shaft 30. In the present instance a pin 31 extends diametrically through the circular bushing 28 and the lower end of the shaft 30 for the purpose of preventing relative rotation of said shaft with respect to the said bushing.

A top closure member 32 for the housing 10 is cast to include a vertical supporting sleeve 33 for the shaft 30 and the lower end of said sleeve portion extends inwardly of the housing 10 as at 34 to prevent upward movement of the bushing 28 and disengagement of the pin 27 from the hole 26 in the cam 23.

40 A bracket 35 is formed integral with the cover member 32, the purpose for which will be set forth hereinafter. A socket 36 is also formed integral with said cover and is intended to slidably receive a pin 37 compressible inwardly thereof against a spring 38. The upper end of the pin 37 is arranged to engage recesses 39 formed in the under side of a stop member 40 having a sleeve 41 which is keyed to the shaft 30, said recesses 39 and the stop 40 being suitably positioned circumferentially of the shaft so that the latter may be releasably held in position when either one of the planetary gears 20 is meshed with the beveled gear 13 or in neutral position.

55 A circular cam disk 42 is eccentrically keyed to the shaft 30 and it should be particularly noted that the position of said cam 42 with respect to the shaft 30 is such that the diameter of the cam which intercepts the axis of the shaft is at an angle of approximately 14 degrees with the diameter of the shaft 30 which is horizontal with respect to Fig. 4 of the drawings, and the purpose for so offsetting the cam 42 will be brought out hereinafter.

60 A substantially L-shaped cam arm 43 is pivotally mounted on the upper end of the cover bracket 35, and a cam roller 45 is mounted at the end of the short arm 46 thereof and arranged to ride upon the periphery of the cam disk 42. A rod 47 is slidably mounted in the clutch lever 9 and connected at one end to the end of the long arm 48 of the cam arm 43. A collar 49 is fixed on the rod 47 to engage the clutch lever 9 and rock the same forward to disengage the engine clutch when the cam arm 43

is pivoted in a clockwise direction with respect to Fig. 5 by the cam disk 42.

As hereinbefore described, the cam disk 42 is positioned so that its diameter which intercepts the axis of the shaft 30 is disposed at an acute angle with respect to the diameter of said shaft horizontally with respect to Fig. 5 and the cam roller 45 contacts the periphery of the cam disk 42 at a position other than on dead center when the shaft 30 is in neutral position.

10 It should be noticed that the relation of the periphery of the cam 42 with respect to the shaft 30 is such that the cam arm 43 is permitted to pivot in a counterclockwise direction to engage the clutch only when said shaft 30 is rotated, by movement of the handle 39a a quarter turn to the right or left with respect to Fig. 5, to mesh either one of the planetary gears 20 with the beveled gear 13.

15 From the foregoing description it will be seen that by meshing one of the planetary gears 20 with the beveled gear 13 on the shaft 11, rotation of the latter will be imparted to the shaft 16 in one direction and by meshing the other planetary gear 20 with said beveled gear 13, 25 rotation of the shaft 11 will be imparted to the shaft 16 in the opposite direction. Consequently it will be obvious that with either one of the planetary gears meshed with the beveled gear 13, the shaft 16 may be driven in that particular direction at each of the various speeds selected by operation of the transmission shift lever 8 in the usual manner.

20 Rotation of the main operating shaft 16 is imparted to one of the axles 4 to propel the machine along the railway track on the traction wheels 6, by means of a chain 50 which passes about a sprocket wheel 51 mounted on said axle and about a sprocket wheel 52 secured to a hub 53 rotatably mounted with respect to the shaft 16 by means of bearings 53a. In the present instance one annular face of the hub 53 abuts the adjacent face of the direction change mechanism housing 10 and movement of the hub 53 longitudinally of the shaft 16 is prevented by a tapered pin 54 which extends diametrically through an annular retaining ring 55 and the shaft 16. The outer annular face of the hub 53 is provided with circumferential jaws 56 which constitute one member of a jaw clutch 50: designated generally as at A, said jaws being arranged to engage complementary jaws 57 formed on the adjacent annular face of a sleeve 58 adapted to rotate with the shaft 16 and is slidably mounted with respect thereto by means of keys 59. In the present instance the jaws 57 of the sleeve 58 are moved into or out of engagement with the jaws 56 on the hub 53 by means of a shift lever 60 pivoted as at 61 to the housing 17a which supports the bearing 17 of the shaft 16. The lower end of the lever 60 is connected by means of a ball and socket joint 63 to a shipper rod 64 connected at its inner end as at 65 to a ring segment 66 which

65 rides in an annular groove 67 formed in the sleeve 58. A spring pressed pin 68 is mounted in the bracket 17a and is arranged to engage recesses (not shown) formed in the shipper rod 64 to releasably lock the shipper rod in its extreme positions when the jaw clutch A is engaged or disengaged respectively. In the present instance a brake drum 69 is mounted on the axle 4 adjacent the sprocket 51 and arranged to rate with said axle internally of a brake shoe 70 which may be tightened about the periphery 75

of the drum 69 to retard rotation of the axle 4 by a brake lever 71 operatively connected to said shoe by rods 72. It will be obvious that when the clutch A is engaged, rotation of the 5 shaft 16 will be imparted to the hub 53 and sprocket 52 to the axle 4.

The grinding mechanism is contained within a casing 73 slidably mounted in any convenient manner upon horizontal runners 74 forming part 10 of a bracket 75 secured to the underside of the side frame and sill members 1 and 3 at each side of the machine. One end wall 73a of the casings 73 is inclined as shown in Fig. 9 of the drawings to provide a space between abrasive elements 76 and one end of the casings for entrance of a wedge member 77 to prevent rocking of said elements 76 during grinding. A bracket 78 extends vertically from the inner wall of each casing 73 and a sleeve 79 having a 15 threaded bore 80 therein is fixedly carried thereby. For the purpose of adjusting the abrasive elements 76 vertically with respect to the rails 7, the jack screws 81 having hand wheels 82 are threaded in the sleeves 79 and connected at 20 their lower ends to a cross head 83 by means of a ball and socket joint, said abrasive elements 76 being suspended from the cross head or piece 83 by means of studs 84 imbedded in 25 said elements.

30. In order to insure uniform constant pressure of the abrasive elements 76 upon the surface of the rails 7 a flange 85 is threaded on the lower end of each of the sleeves 79 and a coil spring inserted between said flange and the overlying 35 web of the bracket 78.

The previously mentioned wedge members 77 are similarly adjustable vertically with respect to the casings 73 by means of hand wheels 86 and jack screws 87 threaded in brackets 88 on 40 said casing. In the present instance the lower end portion of each wedge 77 is slotted to permit passage thereof about a pin 89 which extends inwardly of the inclined end wall of the casing and exerts a lateral outward thrust against the 45 wedge 77 by virtue of a spring 90 compressible between the outer face of the end wall and a collar 91 on the pin 89 for the purpose of maintaining the wedge 77 snug against the end wall 73a to prevent rattling thereof when loosely suspended within the casing.

A tubular bearing 92 forms part of each bracket 75 and a stud shaft 93 is rotatably mounted therein. In the present instance a crank arm 94 having a counterbalance 95 is fixed on the 55 outer end of each stud 93 for rotation therewith and the crank 94 is connected to the adjacent end of the grinding casing 73 by means of a connecting rod 96 attached to said casing by a wrist pin arrangement 97.

60. A sprocket 98 is fixed on the other end of each of the studs 93 and a chain 99 passes about said sprocket 98 and another sprocket 100 mounted for rotation with a shaft 101 rotatably supported at its ends in bearings 102 suspended from a plate 65 103 releasably secured to the top of each bracket 75 intermediate the side frame members 1 and sills 3. The plate 103 is slotted at 104 to permit adjustment thereof longitudinally of the bracket 75 so that slack or play occurring in the chain 99 may be taken up and eliminated.

A sprocket 105 is fixed on the shaft 101 and driven by a chain 106 which is in turn driven by a sprocket 107 on the main shaft 16. The stud 93 is driven through the connections previously 75 described by the shaft 101 and the crank 94 and

connecting rod 97 function to convert the rotary motion of said stud into straight line motion for reciprocation of the grinding mechanism.

In the present instance the sprocket 107 is 5 rotatably mounted on the shaft 16 and is connected to the latter through a jaw clutch designated generally as at B and operated by means of a shift lever 108. The construction of the jaw clutch B and its operation are substantially 10 identical to that described with regard to the jaw clutch A and a detail description thereof is deemed unnecessary.

For the purpose of moving the entire machine 15 from the track to a position at one side thereof, a roller 109 is mounted adjacent each corner of the frame of the machine, and these rollers are mounted in a screw and sleeve mechanism 110 operable to permit said rollers 109 to be lowered for the purpose of elevating the machine sufficiently to raise the flanges of the traction wheels 20 6 clear of the rails 7 to permit removal of the machine transversely of the track. In the present instance, the screw and sleeve mechanism 110 is rotated to raise or lower the rollers 109 with respect to the machine by means of cranks 111 at 25 each end thereof and operatively connected to the lifting devices at that end of the machine through a transverse shaft 112 and beveled gears 113 and 114 respectively.

Operation of the jack screws 81 and 87 to adjust 30 the abrasive elements 76 and wedges 77 respectively is very often difficult during reciprocation of the grinding mechanism especially at high speeds and in order that such adjustment may be readily made during grinding, it may be desirable 35 to provide the construction shown in the modification in Fig. 10 of the drawings wherein the hand wheels 82a and 86a do not reciprocate with the grinding mechanism as is the case when mounted in the manner disclosed in Fig. 9. As 40 shown in Fig. 10 the hand wheels 82a and 86a are fixed with respect to the machine and the shafts 115 and 116, respectively rotated thereby to raise and lower the jack screws 81 and 87 through gearings 117 and 118, are slidably mounted 45 in said hand wheels 82a and 86a, and bearings 119 and 120 respectively and move longitudinally therethrough together with the grinding mechanism. A small clearance as at 120a is provided 50 between the mountings of the shafts 115 and 116 and bearings 119 and 120 to permit proper alignment 55 of the adjusting mechanism at all times.

A tank combining fuel and water compartments 121 and 122 respectively necessary for the 60 operation of the internal combustion engine M is mounted on the frame of the machine adjacent one end thereof and the customary water cooling 65 radiator 123 is mounted adjacent the forward end of said engine M. The engine is provided with the usual self or automatic starting means 124 and fuel feeding control and spark control 70 means 125 and 126 respectively. The entire mechanism previously described is surmounted by a body or carriage which is secured to the upper side of the main frame members of the machine and includes hand railings 127 and floor sections 128 suitably positioned to facilitate proper 75 operation of the machine and prevent injury to the operators which might result from contact with the rapidly moving mechanisms thereof.

In operation of the device and supposing that the machine has arrived at a location along the track where grinding of the rails is necessary, the direction control mechanism is in neutral position and the clutch A has been disengaged, 75

clutch B having been disengaged previously during movement of the machine along the track. The abrasive elements 76 are then adjusted for proper contact on the rails 7 by the hand wheels 82 and 86, and the clutch B is engaged by throwing the lever 108. One of the planetary gears 20 is meshed with the drive gear 13 by turning handle 30a to complete the connection from the motor M to the grinding mechanism, the speed of reciprocation of which may be changed by operation of the clutch 9 and change speed lever 8.

Upon completion of the grinding operation or if an approaching train necessitates rapid removal of the machine from the locus operandi, the direction control is neutralized by turning handle 30a, and clutch B is then disengaged and the elements 76 withdrawn from contact with the rails 7. Clutch A is then engaged by throwing lever 60 and one of the gears 20 meshed with the driving gear 13 by turning the handle 30a to complete the driving connection from the motor M to the axle 4 to propel the machine along the track. It should be particularly noticed that that planetary gear 20 should be meshed with the gear 13 which will propel the machine in the desired direction along the track at the various speeds which may be selected by operation of the shift lever 8, permitting the machine to get away rapidly at high speed by changing from low, through second to high speed ratio of the transmission.

While the preferred embodiment of the invention has been set forth for the purposes of description, it is intended that certain changes and modifications may be incorporated from time to time within the scope of the annexed claims.

Attention is called to the fact that certain features disclosed herein, including features of the transmission mechanism or drive between the engine and the wheels and reciprocating grinder bricks, are described and claimed in my copending application Serial No. 686,312, filed August 22, 1933.

What is claimed is:

1. In a track grinding machine, the combination with abrasive means and means for reciprocating the same, of means operable to adjust said

abrasive means with respect to the track rails, said means including a jack screw, a hand wheel fixedly mounted on the machine independently of said jack screw, a shaft slidably mounted in said wheel and rotatable therewith, and means operatively connecting one end of said shaft with the jack screw to rotate the latter whereby the abrasive elements may be readily adjusted during reciprocation thereof. 5

2. In a track grinding machine, the combination with abrasive means, of a casing therefor slidably mounted with respect to the machine and having one end wall thereof disposed at an angle with respect to the adjacent face of the abrasive means, a wedge member interposed between said face and the end wall of the casing, means operable to regulate the relative position of said wedge inwardly of said casing to prevent movement of said abrasive means longitudinally thereof and spring actuated means extending 10 through said wedge to hold the latter firmly against the adjacent wall of the casing. 15

3. In a track grinding machine, the combination with abrasive means and means for reciprocating the same, of rotatable means operative 20 to adjust said abrasive means with respect to the track rails, a second rotatable means fixedly mounted on the machine independently of said first rotatable means, a shaft slidably mounted in said second means and rotatable therewith, 25 and means operatively connecting one end of said shaft with the first means to rotate the latter whereby the abrasive elements may be readily adjusted during reciprocation thereof. 30

4. In a track grinding machine the combination with abrasive means and a casing therefor slidably mounted with respect to the machine, of a wedge member interposed between said abrasive means and one end wall of the casing, rotatable means operative to adjust said 35 wedge relative to the casing, a second rotatable member mounted on the machine independently of said first rotatable member, a shaft slidably mounted in said second member and rotatable therewith, and means operatively connecting one 40 end of said shaft with the first means to rotate the latter to adjust the wedge. 45

HENRY J. PERAZZOLI.
